UNITED STATES PATENT OFFICE.

JOHN B. CAREY, OF BROOKLYN, NEW YORK.

RAILROAD-GATE.

SPECIFICATION forming part of Letters Patent No. 373,642, dated November 22, 1887.

Application filed March 19, 1887. Serial No. 231,583. (No model.)

To all whom it may concern:

Be it known that I, JOHN B. CAREY, of Brooklyn, in the county of Kings and State of New York, have invented a new and Improved 5 Railroad-Gate, of which the following is a full, clear, and exact description.

The object of my invention is to provide a new and improved railroad-gate specially adapted for platforms of elevated railroads, to 10 avoid accidents to passengers awaiting a train.

The invention consists of a gate or gates held in a closed position by counter-weights and opened by the car-wheels of an approaching train, and in the construction and arrangement 15 of details and parts, as will be hereinafter fully described, and pointed out in the claims.

Reference is to be had to the accompanying drawings, forming a part of this specification, in which similar letters of reference indicate 20 corresponding parts in all the figures.

Figure 1 is a side elevation of my improvement in a closed position and as applied to an elevated railroad, part of which is broken out. Fig. 2 is a similar view of the same, showing 25 the gate open. Fig. 3 is a side elevation of part of the rail-lever and its connection. Fig. 4 is a plan view of my improvement, shown in connection with part of an elevated road. Fig. 5 is a vertical cross-section of the same on the lines $\alpha\alpha$ of Fig. 4, and Fig. 6 is an enlarged 30 vertical cross-section of the gate-lever and its bearing.

My improved railroad-gate is specially adapted for elevated railroads, to form a gate 35 or series of gates at the outer edge of the platform next to the track, which is generally a certain distance below the platform, so that the latter is even with the bottom of the cars when they are drawn up to the station. Along the outer edge of the platform A are erected a number of hollow posts, C, and between each two succeeding ones is held a gate, D, of suitable construction, hung at each 40 end to a rope or chain, E, which passes over a pulley, E', mounted near the top of the post, and carries on its other end, which is incased in the hollow post C, a counter-weight, E², which holds the gate D in a closed position, as 45 shown in Fig. 1. The gate D is connected by the links F F with the inner ends of the levers G G, respectively, each of which is fulcrumed 50 at the pivot G', secured to the platform-frame

A'. The outer weighted end of each lever G is provided with a slot, G², into which projects the pin H', secured to one end of the weighted lever H, pivoted at its other end at H² to the platform-frame A'. On the lower edge of each lever H operates one end of the lever I, arranged at right angles to the levers H and the track B, and pivoted to a bracket, J, secured to and extending outwardly toward the track B from the platform-frame A'. The other end of each lever I is bent upwardly, and its upper edge rests in a groove, K', formed in the lower edge of the rail-lever K, held loosely between 60 the main rail B' and the guard-rail B² of the track B. When the guard-rail B² is not used, then the rail-lever K is held and guarded by suitable brackets secured to the ties in place of the guard-rail B². The weight on each of 65 the fulcrums G' and H² of the levers G and H is taken up by a grooved roller, L, traveling on the segmental edge of a bearing, N, secured to the platform-frame A'. In the upper part of the roller L rests the curved lower edge of 70 the lever G or the lever H, and as the said edge is directly under the fulcrum, it will be seen that the weight and pressure on the levers G, respectively, and the levers H is taken up by 75 their respective rollers L, which permit, however, a free swinging motion of the levers G and levers H, as the centers of the segmental edges in which the rollers N travel are the fulcrums G' and H².

A lever-rail, K, may be used for each gate 80 D, or the said lever-rail K may be made sufficiently long to operate all the gates D on one platform, A. The outer ends of the lever-rails are slightly bent downward, as plainly shown in Figs. 1 and 3.

The operation is as follows: The counter-weights E² in the posts C hold the gates D in a closed position, as shown in Figs. 1 and 5. Now, when a train moves up to a station, then the flanges of the car-wheels pass onto the lever rail or rails K and press the same downward by the weight of the cars, so that the levers I swing in the direction of the arrow a', (see Fig. 5,) and the levers H are swung upward, thereby causing the inner ends of the gate-levers G to swing downward in the direction of the arrow b', so that the gate is also moved vertically downward until the upper edge is below the level of the platform A, as shown in Fig. 2,

thus closing the latter and permitting the passengers to get out or enter the cars. As soon as the train leaves the station and the flanges of the car-wheels are off the lever rail or rails 5 K, then the gates D move vertically upward again by the action of the counter-weight E in the hollow posts C, so that all the different parts again assume the position shown in Figs. 1 and 5. The levers G and the levers H are 10 weighted to assist in raising the gates D again when the car-wheels leave the lever-rails K.

Having thus fully described my invention, I claim as new and desire to secure by Letters Patent—

15 1. In a railroad-gate, the combination, with a rail-lever held alongside of one of the track-rails and operated upon by the car-wheels, of levers supporting the said rail-lever, weighted levers acting upon the latter levers, and additional weighted levers connected to the first weighted levers and carrying the gates, substantially as and for the purpose set forth.

20 2. In a railroad-gate, the combination, with a rail-lever held alongside of one of the track-rails and operated upon by the car-wheels, of levers supporting the said rail-lever, weighted levers acting upon the latter levers, additional weighted levers connected to the first weighted levers, and a counterbalanced gate pivotally 25 connected with said additional weighted levers, substantially as and for the purpose set forth.

3. In a railroad-gate, the combination, with a rail-lever held alongside of one of the track-rails and operated upon by the car-wheels, of levers supporting the said rail-lever, weighted 35 levers acting upon the latter levers, additional weighted levers connected to the first weighted levers, links pivoted to the said additional weighted levers, and a counterbalanced gate pivotally connected with said links, substantially 40 as and for the purpose set forth.

4. In a railroad-gate, the combination, with the rail-lever K, having the notches K', of the levers I, held with one end in the said notches, the pivoted arms H, operated by the levers I, 45 the pins H', secured to the said arms H, and the gate levers G, pivotally connected with the gate, and each having a slot, G², in which operates the said pin H' of the respective arm H, substantially as shown and described.

5. In a railroad-gate, the lever G, having the slot G²; and the arm H, provided with the pin H', operating in the said slot G², in combination with the rollers L and the bearings N, each supporting on a segmental edge one of 55 the said rollers L, substantially as shown and described.

JOHN B. CAREY.
